UNITED STATES PATENT OFFICE.

WALTER CARTWRIGHT, OF NEW YORK, N. Y.

TILE.

SPECIFICATION forming part of Letters Patent No. 629,337, dated July 25, 1899.

Application filed April 20, 1899. Serial No. 713,728. (No model.)

To all whom it may concern:

Be it known that I, WALTER CARTWRIGHT, a citizen of the United States, residing at New York, (Brooklyn,) in the county of Kings and State of New York, have invented certain new and useful Improvements in Tiles, of which the following is a specification.

This invention relates generally to tiles and specifically to that form of tiles known technically as the "angle-beads"—that is, the tiles used in finishing the corners where angles are formed by the flat tiles terminating.

The object of this invention is to obviate the present difficulties encountered in tiling corners, which is principally the tendency of said tiles to fall off when subjected to excessive heat or moisture. When the ordinary angle-bead is placed in position, it rarely presents its entire inner surface to perfect contact with the cement and will in consequence be easily loosened and either fall off or shift its position and destroy the symmetry of the tiled surface.

This invention discloses an angle-bead provided on its back with an anchor or formation adapted to be buried in the cement in such manner that it will be impossible after the cement has set for the tile to be loosened or move sufficiently to destroy the alinement of the tiled surface.

In the accompanying drawings, which form a part of this specification, Figure 1 is a horizontal section of a portion of a wall, showing the angle-bead in position. Fig. 2 is a perspective view of one of the angle-beads. Figs. 3 and 4 are detail perspective views of modified forms of the anchors.

Similar numerals indicate like parts in the several figures.

In the construction and application of my invention 1 is a rough brick or stud partition having a scratch-coat of cement 2, secured to lathing of any desired kind.

3 is a backing or body of cement in which the flat tiles 4 are laid and by means of which they are held in position.

5 is the angle-bead, presenting rounded outer and inner surfaces 6 and 7, respectively. The surfaces 8 of the angle-bead abut the flat tiles 4 when said angle-bead is placed in its proper

position, as indicated in Fig. 1. The angle-bead is preferably made thicker than the flat tiles, so that flat tiles of varying thickness can be employed and the outer-surface alinement of the tiles be preserved. The angle-bead is 55 always forced into the cement 3 until the outer surface 6 thereof is flush with the flat tiles 4. By making the angle-bead of greater thickness than the flat tile the cement 3 is allowed to come in contact with the surfaces 8, 60 and thereby form a more positive anchor.

Extending outwardly from the surfaces 8, are longitudinal ribs 10, which are embedded in the cement 3 and are designed to form the anchor proper for the angle-bead. The cement 3 will be squeezed in between the ribs and the flat tiles, so that after the cement has "set" the angle-bead will be securely anchored in the desired position and cannot be moved or loosened by the varying conditions 70 of the atmosphere or in cleaning or in the settling of the walls.

In Fig. 3 I have shown a modified form of anchor for the angle-bead, wherein a central longitudinal rib 12 is used in addition to the 75 longitudinal ribs 10. This central rib 12 is narrowest transversely where it connects with the angle-bead, so that when the angle-bead is forced into the cement said cement will bear against the surfaces 13 on the central rib, thereby making an additional anchor.

In Fig. 4 a further modified form of the angle-bead is shown, wherein a series of formations 14 are used that are similar in cross-section to the central rib 12, Fig. 3, and are held 85 by the cement 3 in the same manner as said central rib.

Having thus described my invention, what I claim as new therein, and desire to secure by Letters Patent, is—

An angle-bead of greater thickness than the flat tile and having curved inner and outer surfaces, longitudinal ribs on the inner surface and the flat surfaces of said angle-bead adapted to abut the terminating ends of the 95 flat tiles as explained.

WALTER CARTWRIGHT.
